UNITED STATES PATENT OFFICE.

DANIEL F. SHOUP, OF LUDINGTON, MICHIGAN, ASSIGNOR OF ONE-HALF TO
CARTER SMEDLEY, OF SAME PLACE.

PACKING AND BARRELING MACHINE.

SPECIFICATION forming part of Letters Patent No. 394,305, dated December 11, 1888.

Application filed January 9, 1888. Serial No. 260,148. (No model.)

To all whom it may concern:

Be it known that I, DANIEL F. SHOUP, of Ludington, in the county of Mason and State of Michigan, have invented a new and Improved Packing and Barreling Machine, of which the following is a full, clear, and exact description.

This invention relates to a machine arranged for the packing of salt, sugar, cement, or other like materials in barrels, the object of the invention being to provide for the transfer of the salt or other material from a pile to the barrels and for the adjustment of the various parts of the salt-delivery mechanism to such position relatively to each other as may be required within the packing-room without any change of the main shaft-supporting frame.

Reference is to be had to the accompanying drawings, forming a part of this specification, in which similar figures of reference indicate corresponding parts in all the views.

Figure 1 is a plan view of my improved packing and barreling machine. Fig. 2 is an enlarged sectional detail view representing a portion of the revoluble platform upon which the salt-receiving barrels rest. Fig. 3 is an enlarged detail view illustrating the arrangement employed for tightening the driving belt or chain. Fig. 4 is a side view of the machine. Fig. 5 is a central longitudinal sectional view representing the lower portion of the elevator-belt and its connections and the lower portion of the delivery-belt and its connections. Fig. 6 is a detail view of the barrel-supporting disk or platform, the standards extending upward therefrom being shown in section. Fig. 7 is an enlarged central sectional elevation of the machine; and Fig. 8 is a detail view, wherein the central standard is shown in section, the view being given to illustrate the arrangement of the clutch arranged in connection with the supporting-rod of the packer-shaft. Fig. 9 is a sectional detail view taken on line *x x* of Fig. 5.

In the drawings above referred to, 10 represents a supporting-frame, in the upper portion of which there is journaled a vertical shaft, 11, upon which is loosely mounted a pulley, 12, with which the shaft can be held to revolve by means of a clutch, 13. To the

lower end of the shaft 11 is connected a bevel-gear, 14, which meshes with a corresponding gear, 15, integral with a sleeve, 15^a, journaled in the uprights 10^a of frame 10. A horizontal shaft, 16, passes loosely through the sleeve, which shaft for a portion of its length is squared or irregularly formed, as shown at 17, to fit the correspondingly-shaped bore of the sleeve 15^a, whereby the shaft may be moved longitudinally within the sleeve and gear, but will necessarily follow any rotative movement of the gear. The frame 10 is provided with dogs 18, which are driven into the floor in order that the frame may be held in rigid immovable position. The other end of the shaft 16 is supported in bearings that are carried by a column, 20, which column is in turn supported by a base, 21, that is provided with dogs 22, by which it is connected to the floor. Just beyond the column 20 the shaft 16 carries a bevel-gear, 23, which gear engages with a double-faced bevel-gear, 24, that is carried by a sleeve, 25, said sleeve being mounted to turn in bearings 25^a, which extend outward from the column 20.

The upper section of the gear 24 engages a bevel-gear, 26, which is carried by a shaft, 27, journaled in an elevator-head, 26^a, of an elevator, A, supported to turn on the sleeve 25 by arms 27^a. On the shaft 27 there is mounted a sprocket-wheel, 28, which carries a chain belt, 29, the lower end of the belt passing over a sprocket-wheel, 30, the shaft of which is journaled in arms 31, (see Fig. 3,) 85 said arms being pivotally connected to the side walls of a lower hopper, 32, clamping-bolts 33 being arranged to pass from the hopper-walls through circular slots formed in the arms 31, the arrangement being such that by 90 swinging the arms downward upon their pivotal connection the chain belt 29 may be tightened, as will be readily understood. The chain 29 carries elevator-buckets 34, which run in troughs 35 and deliver their contents 95 to a hopper, 40, which is connected to one side of the column 20. From the elevator-head 26^a a chute, 40^a, extends into the hopper 40, which chute at its outer side is provided with a roller, *a*, bearing on the edge of the hopper 100 40. By the construction above described the base 21 and parts carried thereby can be ad-

justed to and from the frame 10, and the elevator A can be swung to extend in any direction from the hopper 40.

Upon the base 21, I mount a platform, 41, 5 one quarter-section of which is cut away, and in the space so formed I mount a scale-platform, 42, which is connected in the usual manner with a beam, 43, which extends outward from one side of the column 20. Above the 10 platform 41, I mount a revoluble platform, 44, which carries four segmental sections, 45, which sections are connected to the main portion of the platform by links 46. To the under side of the segments 45, I secure rollers 47, 15 which ride upon the upper face of the platform 41.

Above the platform 44, I mount a third platform, 48, in which there are formed four apertures, 49, this platform 48 being supported 20 by posts 50, which extend upward from the platform 44. In the peripheral edge of the platform 44, I form a number of recesses, 51, which are engaged by a spring-catch, 52, the catch being so placed as to hold the platform 25 48 so that its apertures 49 will register with the lower open end of the hopper 40.

In the column 20, I arrange a rod, 54, which is normally upheld by a friction-catch, 55, and the upper end of this rod 54, I bend over, 30 as shown best in Fig. 7, this bent-over section serving as the support for a squared or irregularly-formed shaft, 56, which extends down through the corresponding bore of the sleeve 25 and carries at its lower end a packer, 35 57, which packer is preferably made in the form of two cones, the apices of which are united.

To the bent-over section 58 of the rod 54, I connect a chain or cord, 59, which extends 40 upward over a sheave, 60, a ring or handle, 61, being connected to the free end of the chain or cord, so that by drawing down upon the handle the rod 54 and the shaft 56 carried thereby will be raised, or by releasing 45 the catch 55 the shaft 56 will drop, so that its packer 57 will enter the barrel beneath the hopper 40, the packer and shaft being shown in this lowered position in Fig. 7.

To the shaft of the wheels 30, I connect a 50 gear, 62, which engages a pinion, 63, that is mounted upon the shaft of a drum or sprocket-wheel, 64, which said drum or sprocket-wheel serves as the support for a chain belt, 65, which carries a number of outwardly and 55 laterally extending teeth, 66, the outer end of the belt being supported by a drum, the shaft of which is mounted in bearings formed in plates 67, said plates being adjustably connected to a timber, 68, so that the tension of 60 the belt may be regulated as desired, similar plates, 70, being connected to the inner end of the timber in position to support the bearings of the drum or wheel 64.

The drum or sprocket-wheel 64 is rigidly 65 connected to its shaft, and the inner end of the shaft is mounted in a sleeve, 71, to which the approaching plate 70 is secured, the other

plate—that is, the one nearer to the pinion 63—being loosely mounted on the shaft of the drum 64. To the outer end of the sleeve 71 70 there is connected a lever, 72, so that the timber 68 and the parts carried thereby may be thrown upward in the direction of the arrow shown in Fig. 4, the downward throw of the timber being limited by a bar, 74, which 75 bears against the upper edge of the hopper 32, by which construction and arrangement the belt 65 may be adjusted at any desired angle to the elevator A.

In operation the driving belt or chain 75 80 passes from the driving-pulley 76 to the pulley 12, around which it is wrapped, and then passes to a stationary pulley, which may be located at the opposite side of the room, from which arrangement it will be seen that the 85 frame 10 may be shifted toward or from the driving-pulley 76. The parts having been adjusted, a proper motion is imparted to the driving-belt to move the chain 29 in the direction of the arrow shown in Fig. 4, the belt 90 65 at this time moving in the direction of its arrow and resting upon a pile of salt or material to be packed. As the belts so move, the teeth 66 will cut through the salt and will carry it downward into the hopper 32 to the 95 buckets 34 of the belt 29, which buckets will carry the material upward and into the hopper 40. From thence it will pass into a barrel located directly beneath one of the openings 49, which openings are held in register with 100 the lower open end of the hopper by the spring-catch 52. As the salt or other material passes into the barrel, the packer 57 is permitted to drop into the barrel and is revolved, so as to act to compress the salt. After 105 the salt has been properly compressed the handle 61 is grasped and the packer is raised to a position within the hopper 40. The spring-catch 52 is then released, and the platform 44, and with it the platform 48, is turned 110 so that the packed barrel will be moved toward the scale, where it is weighed, the filled barrel being then removed and replaced with an empty one.

As the platforms 44 and 48 are revolved, as 115 above described, all discharge of salt or other material from the hopper will be prevented, owing to the fact that the platform 48 will act as a cut-off, the only openings in said platform being directly over the barrels carried 120 by the platform 44. After a kerf has been cut in the pile of salt or other material the parts are shifted, so that the teeth of the belt 65 will bear upon a new portion, and after a number of kerfs have been cut in the pile the 125 standing walls between the kerfs are broken and a pile formed from the residuum.

From the foregoing description it will be understood that the parts carried by the base 21 can be adjusted toward or from the frame 10, while the elevator A may be moved so as to extend at most any desired angle from the hopper 40. This, together with the fact that the frame 10 can be adjusted toward or from

the driving-pulley, provides for the operation of the various parts of the mechanism in almost any desired position relatively one to the other.

5 Having thus fully described my invention, I claim as new and desire to secure by Letters Patent—

1. In a packing and barreling machine, the combination of a hopper, an elevator emptying into the same, means for operating the elevator, and a rotary packer connected with and operated by the elevator-operating mechanism, substantially as described.

15 2. In a packing and barreling machine, the combination of a hopper, an elevator emptying into the hopper, a rotary packer, and the elevator and packer driving mechanism above the hopper, and around which the elevator is fitted to swing, substantially as herein shown 20 and described.

25 3. In a packing and barreling machine, the combination, with a fixed platform provided with a platform-scale, of a movable platform mounted above the fixed platform and provided with segmental roller-supported traps, a hopper, a cut-off arranged in connection therewith, an elevator-belt arranged to deliver the material to the hopper, and a means for driving said elevator-belt, substantially as 30 described.

35 4. In a packing and barreling machine, the combination, with a frame, 10, of a pulley supported thereby, a driving-belt passing around said pulley, a driving-pulley and a guiding-pulley, a gear controlled by the first-named pulley, a second gear engaged thereby and supported by a squared or irregularly-formed shaft, an elevator-belt, connections between said belt and the squared or irregularly-formed 40 shaft, whereby the elevator belt or chain is driven, a delivery belt or chain arranged in connection with the elevator-belt, a hopper, and a cut-off arranged in connection with said hopper, substantially as described.

45 5. In a packing and barreling machine, the combination, with a frame, 10, of a pulley, 12, carried thereby, a gear, 14, connected to the pulley, a gear, 15, that is engaged by the gear 14, a shaft, 16, formed with a squared or 50 regularly-formed section, 17, which passes through the gear 15, a gear, 23, carried by the shaft 16, a double-faced gear, 24, that is engaged by the gear 23, a gear, 26, also engaged

by the double-faced gear, a drum or sprocket-wheel, 28, a bucket-carrying chain or belt supported thereby, a lower supporting-drum arranged in connection with the belt, a hopper within which the drum revolves, a gear carried by the drum-shaft, a pinion, 63, engaged by said gear, a chain or belt, 65, carrying 60 teeth 66, connections between said chain or belt and the pinion 63, a sleeve upon which the double-faced gear 24 is mounted, a squared or irregularly-formed shaft passing through said gear, a packer carried by the shaft, a 65 hopper arranged to receive the discharge of the elevator-belt, and a cut-off arranged in connection with the hopper, substantially as described.

6. In a packing and barreling machine, the combination, with a fixed platform, 21, provided with a scale-platform, of a revoluble platform, 44, mounted above the fixed platform and carrying segmental traps, a disk, 48, formed with apertures connected to the 75 platform 44, a hopper arranged above the disk, a packer, 57, a means for revolving said packer, a shaft, 54, which supports the packer-shaft, and a catch arranged in connection with said shaft or rod 54, substantially as described.

7. In a barreling and packing machine, the combination, with a supporting-frame and a hopper carried by the frame, of an elevator-head pivoted to the frame, a shaft journaled 85 in the said head and provided with a bevel-gear, a sleeve fitted to turn in the frame, a double-faced bevel-gear on the sleeve, a longitudinal shaft provided with a bevel gear-wheel meshing with the gear on the sleeve, 90 a packer-shaft projecting through the said sleeve, and means for operating said horizontal shaft, substantially as described.

8. In a barreling and packing machine, the combination, with a supporting-frame and a 95 hopper carried thereby, of a scale-platform in the base of the frame and a rotary platform above the base, and an apertured platform carried by the rotary platform and arranged below the bottom of the hopper, substantially 100 as herein shown and described.
